COMMUNICATION METHOD AND SYSTEM

Clarence W. Hansell, Port Jefferson, N. Y., assignor to Radio Corporation of America, a corporation of Delaware

Application June 26, 1942, Serial No. 448,579

10 Claims. (Cl. 250—6)

In this application I disclose a new and improved method of and means for signalling at radio frequency, high frequency and ultra-high frequency.

As is known, the quality of a received signal depends largely on the carrier amplitude and if the same is reduced relative to the sideband or sidebands during transmission due to fading or other causes, distortion at the receiver results. Furthermore, as is known, two carriers separated in the frequency spectrum have entirely different fading characteristics so that one may be received in good strength when the other has faded out and vice versa.

I have provided a new and improved method and means for communication wherein the benefits of frequency diversity are obtained along with an improvement in operation efficiency.

In describing my invention in detail reference will be made to the attached drawing, wherein

Figure 1 illustrates diagrammatically a transmitter system arranged to carry out my method of communication;

Figure 2 illustrates a receiver arranged to make use of and derive the benefits from energy transmitted by my system of Figure 1;

While Figure 3 is a vector diagram illustrating the manner in which the carrier and sidebands are derived for transmission in a system of Figure 1.

In my system I provide at A and B two carrier waves of the desired frequency separation and feed both of these waves into a common amplifier system at C.

One of the carriers, say, for example, the one from A, has a strength considerably greater than the other carrier from B. A 2:1 ratio of strength is satisfactory in many cases. The amplifier C also includes a current amplitude limiter to take out all amplitude variations of the carriers and variations due to combining the carriers. At the output of C I derive a phase modulated wave having a carrier, the frequency of which corresponds to the frequency of the stronger carrier, that is, the one derived at A, and two principal side frequencies on opposite sides of the first carrier spaced from the said first carrier by the frequency difference of the original carriers.

The frequency separation of the two carriers at A and B, Figure 1, is determined by the conditions of operation, the frequency spectrum available for my communication system, the nature of the messages being transmitted and the frequency of operation of the system. Distortion which may be entirely unacceptable in telephony

systems might be acceptable in telegraphy systems. Therefore, in a telegraphy system attenuation of the carrier relative to the sidebands is less harmful than in telephony systems. It has been found that a small separation of two waves of the order of 10,000 to 20,000 cycles is sufficient to reduce greatly the probability of both waves fading out to a point at which distortion results simultaneously. Moreover, at the receiver selective circuits can readily separate currents of frequencies differing by this amount and amplify the same.

That the weaker current from B modulates the phase of the stronger current from A when the combined currents are passed through a limiter will be apparent to those skilled in the art by reference to Figure 3. The weaker current from B represented by vector 4 is added vectorially to the stronger current from A represented by vector 6 at angles varying uniformly with respect to time at a rate of 360° per cycle of beat between them. This means that the resultant, or combined currents, represented by vector 8 varies in both amplitude and phase with respect to the stronger initial current represented by vector 6. It also is seen that the resultant current represented by vector 8 is equivalent in frequency to the stronger initial current with both amplitude and phase modulation added due to the weaker initial current. The resultant current deviates in phase through an angle θ, and is modulated in amplitude (disregarding losses, etc., in the system) through a range twice the amplitude of the weaker of the two currents.

The amplifier and limiter in C, however, remove all variations in strength of the resultant current represented by vector 8 through a range 10, Figure 3, but leaves all variations in phase thereof. The resultant current after elimination of amplitude modulation is a phase modulated current which may be represented or built up from steady state sinusoidal currents corresponding approximately to a carrier and two side frequencies. Consequently, a weaker initial current can be made to phase modulate a stronger initial current by combining the two and passing them through an amplitude limiter.

Assume, for example, that of the original carriers, that supplied by A of Figure 1 is a strong carrier of 15,000,000 cycles per second and that supplied by B is a weaker carrier of 14,990,000 cycles per second. When these two carriers are combined and limited to constant amplitude, the result is a new phase modulated wave having a carrier of 15,000,000 cycles and side frequencies

of 14,990,000 cycles and 15,010,000 cycles. The limiting of the amplitude of the combined currents to a constant amplitude automatically produces two equal side frequencies, one on each side of the stronger current the amplitude of each of which is one-half the amplitude of the smaller original current, measured in percentage of the amplitude of the stronger current.

In other words, if the carrier from A is the stronger carrier and is of frequency fs , while the carrier from B is the weaker carrier and of frequency fw at the amplifier-limiter stage in C, we will have a combined wave such that from the output of C we may derive three main frequencies, one being $fs + (fs - fw)$ corresponding to an upper sideband, fs corresponding to a new carrier, and $fs - (fs - fw)$ corresponding to a lower sideband.

If the weaker of the original carriers has an amplitude of one-half the amplitude of the stronger original carrier then, after combining and limiting, the strength of each of the two side frequencies of the new phase modulated wave will be one-quarter that of the carrier. In other words, combining and limiting two unequal carriers substantially splits the relative energy of the weaker of the two carriers into two parts of half the original relative amplitude, one at the original frequency and one symmetrically spaced in frequency with respect to the stronger of the original carriers. To obtain practically undistorted phase modulation of the stronger carrier by the weaker carrier, the ratio of the two original carrier amplitudes should never be allowed to become less than 2:1 under any conditions of modulation.

By modulating the weaker of the two currents, that is, the one derived from B in Figure 1, I produce out of C the equivalent of two new carriers both modulated in accordance with the signals and symmetrically spaced with respect to the original carrier of the stronger frequency. These two new carriers may then be supplied to the amplifiers and frequency multipliers in D amplified to desired extent and multiplied in frequency and transmitted. Frequency multiplication of the combined and amplitude limited currents increases the phase deviation of the new frequency multiplied current and allows a larger ratio of the amplitudes of the two initial currents to be used.

At the receiver, the transmitted waves are picked up and supplied through selective circuit and amplifier E, the function of which is to pass and amplify the transmitted waves but to reject other waves not in the same frequency band. After amplification, the waves are heterodyned to lower frequencies in detector H and supplied to intermediate frequency amplifiers K and L. The amplifiers K and L are frequency selective so that K passes one modulated sideband of frequencies and L passes the other. Outputs from amplifiers K and L are passed on to detectors M and N respectively having output transformers T₁ and T₂ with their secondary windings coupled for addition of the modulating currents from the detectors. The receivers by responding to the modulated sideband waves of different frequency make use of frequency diversity to reduce distortion resulting from selective fading.

The weaker carrier at B of Figure 1 may be modulated in amplitude, in phase, or in frequency, provided the detectors M and N of Figure 2 are designed to demodulate the corresponding type of modulation. In any case, as has been illustrated in Figure 3, the weaker current will modulate the phase of the stronger current, so that the

two new carriers sideband-like related to the stronger current will be modulated in amplitude, in phase, or in frequency in accordance with the modulations on the weaker current.

Under the conditions described the strongest original carrier will contain a considerable part of the total transmitter power after combination and limiting. However, by adjusting the relative strengths of the two carrier currents, and by multiplying the frequency of the combined and limited wave a selected amount, the energy at the strongest original carrier frequency, in the final output from the transmitter, may be reduced to any desired extent even down to zero. The manner in which this carrier may be controlled in amplitude by controlling the degree of its phase modulation has been described in detail in my U. S. Patent No. 2,169,357, dated August 15, 1939.

In practice it is preferable to use a rather large ratio of amplitudes of the two carrier currents in the transmitter and to use a rather large ratio of frequency multiplication of the combined and limited currents.

It is, of course, necessary that the frequency of the stronger current be equal to the desired mean output frequency of the transmitter, divided by the frequency multiplication ratio and that the difference between the frequencies of the two carrier currents be equal to half the frequency difference desired between the two modulated sideband currents which are to be separately demodulated in the receiver.

In the system described the power output from the transmitter, corresponding to the vector sum of all the component frequency currents, is constant and the transmitter may operate at full class C, high efficiency output.

Also, if desired, the modulations of the carrier wave may be utilized as a third communication channel which is amplitude modulated oppositely to the two side frequency channels. That is, if the weaker of the two original carriers is to be amplitude modulated by the signal, then the modulation of the side frequencies and the modulation of the carrier will be opposite to one another in such a manner that the total power is constant.

For ultra-high frequency communications over short distances the weaker of the two carriers should preferably be frequency modulated since in this case frequency modulation is preferable to amplitude or phase modulation. For this type of transmission a virtue of the system is that interference from another transmitter, produced either by accident or by design, is unlikely to jam or block both channels simultaneously and communication is more likely to be maintained in spite of interference.

I claim:

1. In a transmission system, a source of wave energy of a first frequency and a given amplitude, a source of signal modulated wave energy of a second frequency and of an amplitude considerably less than the amplitude of said first named source, a current amplitude limiter having an input coupled to both of said sources, and wave transmitting means coupled to the output of said limiter.

2. In a communication system, a source of wave energy of a first frequency and a given amplitude, a second source of modulated wave energy of a second frequency and of an amplitude less than said given amplitude, a current amplitude limiter having an input coupled to said sources and having an output, signal transmitting means coupled

to said output, and a receiver having a plurality of frequency selecting and demodulating means, and means for combining the outputs of said demodulating means.

3. In a transmission system, a source of wave energy of a first frequency and a given amplitude, a source of signal modulated wave energy of a second frequency and of an amplitude considerably less than the amplitude of said first named source, a current amplitude limiter and frequency multiplier having an input coupled to both of said sources, and wave transmitting means coupled to the output of said limiter and frequency multiplier.

4. In a communication system, a source of wave energy of a first frequency and a given amplitude, a second source of modulated wave energy of a second frequency and of an amplitude considerably less than said given amplitude, a current amplitude limiter and frequency multiplier having an input coupled to said sources and having an output, signal transmitting means coupled to said output, and a receiver comprising a plurality of selective means and signal detecting means responsive to said transmitted energy and means for combining the outputs of said detecting means.

5. In a transmission system, a source of wave energy of a first frequency and a given amplitude, a second source of signal modulated wave energy of a second frequency and of an amplitude considerably less than said given amplitude, a current amplitude limiter having an input coupled to said sources and having an output wherein appears wave energy including a carrier of said first frequency and side frequencies comprising modulated carriers on opposite sides of said first carrier and spaced therefrom by the difference between said first and second frequencies, and signal transmitting means coupled to said output.

6. A system as recited in claim 5 wherein a frequency multiplier is included in the coupling between said current amplitude limiter and said transmitting means.

7. In a transmission system, a source of wave energy of a first frequency and a given amplitude, a second source of modulated wave energy of a second frequency and of an amplitude about one-half of said given amplitude, a current amplitude limiter having an input coupled to said sources and having an output wherein appears wave energy including a carrier of said first frequency and side frequencies comprising modulated carriers on opposite sides of said first carrier and spaced therefrom by the difference between said first and second frequencies, and signal transmitting means coupled to said output.

8. A system as recited in claim 7 wherein a frequency multiplier is included in said coupling between said current amplitude limiter and said transmitting means.

9. In a transmission system, a source of wave energy of a first frequency and a given amplitude, a source of wave energy of a second frequency the timing of which is modulated in accordance with signals, said second mentioned wave energy being of an amplitude considerably less than the amplitude of the wave energy of said first frequency, a current amplitude limiter having an input coupled to both of said sources, said current limiter having an output wherein appears wave energy including a first carrier of said first frequency and side frequencies comprising timing modulated carriers spaced from said first carrier by the difference between said first and second frequencies, and wave transmitting means coupled to the output of said current limiter.

10. A receiver for wave energy sent out by the system of claim 9 including an amplifier for all of said components of said limiter output, a frequency converter coupled to said amplifier, selective circuits for deriving from the converter the side frequencies, a timing modulation detector coupled to each selective circuit, and a signal combining circuit coupled to the detectors.
